BRASSIÈRE

Marie Marguerite Gil née Dambrun,
Amsterdam, NetherlandsApplication July 19, 1951, Serial No. 237,591
In France July 29, 1950

2 Claims. (Cl. 2—42)

1

This invention relates to brassières or bust bodies for ladies' wear, which, as is known, are intended, by the combined action of shoulder straps and a usually elastic link connecting, at the wearer's back, lateral extensions from breast pockets, to oppose tendency of the breasts to sag laterally and downwardly.

It is found that the greater the tension of the link connecting the lateral extensions, the greater the tendency which brassières of the usual form have to flatten the breasts, and this is particularly undesirable. Moreover, this tension of the back link tends to conceal the natural hollow between the breasts so that they appear as a single, unattractive shape. Finally, most existing brassières are only partially successful in overcoming the tendency to lateral sagging of the breasts.

The principal object of the present invention is to improve the efficiency of brassières in supporting and maintaining the natural hollow between the breasts.

The invention is applied to a brassière, of a known kind, including two breast caps of flexible material, joined together at their inner edges over a width substantially less than the base diameter of the caps, and a frontal elastic member extending between and attached to the lower borders of the caps, the elastic member being adapted to be in tension when the brassière is in place, and, according to the invention, there is provided in each cap, in combination with the above features, a reinforcement of inextensible fabric having the shape substantially of half a frustum of a cone and covering the inside surface of the outer part of the respective cap, the arcuate inner edge of each reinforcement extending concavely from the middle of the upper border of the respective cap to the middle of the lower border thereof and defining a contour at substantially half breast-height, the reinforcement thus being adapted to espouse and support the outer curve of the breast from the base up to substantially half-way to the point of the breast.

The above features combined in a brassière tend to accentuate the points of the breasts while preserving the hollow between them and opposing the tendency to lateral and downward sagging thereof.

The brassière of the invention is otherwise of conventional construction, having lateral extensions from the breast caps to pass around to the back of the wearer and there be linked together, preferably by an elastic and adjustable link, and having a pair of shoulder straps as usual each

2

connected at the front end to the middle of the upper border of the respective cap and at the rear end to the respective extension near the end thereof.

5 A further feature of the invention is that the reinforcement is secured to each cap by an undulating or zig-zag line of stitching running from one end to the other alternately between the inner edge of the reinforcement and the region of the base of the cap. This arrangement avoids the constriction of the breast and the consequent interruption of the smoothness of the curve which a reinforcement stitched along its edge always causes.

10 15 The reinforcement preferably consists of a piece of sparterie or tailor's linen between two similarly shaped pieces of woven fabric.

The invention is illustrated, by way of example, on the accompanying drawings, in which:
20 Fig. 1 is a diagrammatic front elevation showing part of a brassière according to the invention in position of use.

Fig. 2 is a section on the line II—II of Fig. 1.
Figs. 3 and 4 show in elevation, from the out-

25 side and inside respectively, one example of a brassière according to the invention.

Fig. 5 is a section on a larger scale along the line V—V of Fig. 4, and

30 Fig. 6 shows in outside elevation a modified form of brassière.

Referring to Figs. 1 and 2 of the drawings, B₁ and B₂ show very diagrammatically the two caps of a brassière, fitting over the breasts S₁ and S₂, and joined together at their inner edges over a width much less than the diameter of the bases and preferably equal to half thereof. b₁ and b₂ indicate respectively the front point of attachment of the shoulder strap to the respective cap and d₁ and d₂ the middle of the lower part of each cap.

40 45 In accordance with the invention, the lower parts of the caps B₁, B₂ are connected by an elastic band L attached close to the positions d₁, d₂ and of such length that it is in tension when the brassière is on the chest and exerts pull in the directions of the arrows f₁ and f₂.

The inside of each cap is provided with a reinforcement R₁, R₂ of inextensible fabric, hatched in Fig. 1, which assumes the shape substantially of half a frustum of a cone, its base extending between the front point of attachment of the shoulder strap b₁, b₂ to the middle d₁, d₂ of the lower part of the cap.

50 55 It will be understood that this reinforcement, for example R₁, held up at b₁ by the shoulder

3

strap, pressed against the body by the part outside its base owing to the pull of the back link on the extensions from caps and subjected, at d_1 , to the pull indicated as the force f_1 , opposes lateral as well as downward sagging of the breast. Lastly, the two forces f_1, f_2 oppose each other so that the middle part of the brassière, joining the two caps, lifts. These forces preserve the natural hollow between the breasts, keeping the line ac against the chest, thus promoting pointed formation of the breasts.

Figs. 3 and 4 show in detail an embodiment of the brassière of which the principle has been explained.

The caps B_1, B_2 of flexible material, such as woven fabric for example, are shaped by substantially straight line, horizontal, cut darts p_1, p_2 and two slightly incurved cut darts p_1^1, p_2^1 . The adjacent edges of the caps are joined by a seam the length of which is equal to about half the diameter of the base of the caps. The elastic band interconnecting the lower parts of the caps is contained in a tubular cover E accordion pleated so as not to restrict extensibility.

The inside surface of each cap B_1, B_2 is made in one with a reinforcement R_1, R_2 consisting for example (see Fig. 5) of a layer t of tailor's linen or sparterie between two layers s of satin of the same dimensions.

The reinforcement, which is bound along g_1 and g_2 , is secured in the cap at one side by a row of stitching h_1, h_2 along the joining line of each cap with its lateral extension and along its inner border by a star outline of stitching i_1, i_2 which runs alternately to and from the inner edge of the reinforcement which is about halfway up the cap.

The modified form of brassière shown on a smaller scale by Fig. 6 differs from that above described in that the narrow elastic band L is replaced by a panel of elastic fabric T which is stitched to the lower edges of the caps and to downward portions of the lateral extensions of the brassière, the width of the extensions being increased for this purpose. This panel of elastic fabric must in all cases be absolutely sepa-

rate from the junction or middle part of the brassière joining the two caps.

I claim:

1. In a brassière including two breast caps of flexible material, joined together at their inner edges over a width substantially less than the base diameter of said caps, and a frontal elastic member extending between and attached to the lower borders of said caps, said elastic member being adapted to be in tension when the brassière is in place, the combination in each said cap of a reinforcement of inextensible fabric having the shape substantially of half a frustum of a cone and covering the inside surface of the outer part of the respective cap, the arcuate inner edge of each said reinforcement extending concavely from the middle of the upper border of the respective cap to the middle of the lower border thereof and defining a contour at substantially half breast-height, each said reinforcement thus being adapted to espouse and support the outer curve of the breast from the base up to substantially half-way to the point of the breast.

2. A brassière according to claim 1, in which each said reinforcement is secured in the respective cap by stitching extending to and from across said reinforcement and defining a zig-zag line from the upper border to the lower border of the respective cap, the angles of said zig-zag line being located alternately at said inner edge of said reinforcement and towards the outer edge thereof in the region of the base of the respective cap.

MARIE MARGUERITE GIL
NÉE DAMBRUN.
